(57) **CLAIM**

The ornamental design for a dental curing light, as shown and described.

DESCRIPTION

FIG. 1 is an upper perspective view of a dental curing light shown with a symbolic break;

FIG. 2 is an upper perspective view thereof that is enlarged relative to FIG. 1;

FIG. 3 is an enlarged upper perspective view thereof shown in an alternate configuration of use and with a symbolic break;

FIG. 4 is a lower perspective view thereof; and,

FIG. 5 is a cross-sectional view thereof taken along line 5-5 in FIG. 4 shown with a symbolic break.

The broken lines immediately adjacent the shaded areas represent the bounds of the claimed design, while all other broken lines are directed to environment and are for illustrative purposes only; the broken lines form no part of the claimed design. FIG. 1 shows an unclaimed portion of the dental curing light with a symbolic break in its length. The
